UNITED STATES PATENT OFFICE

163,762

FLUORESCENT LIGHTING FIXTURE

Clyde D. McCann, Des Moines, Iowa

Application June 5, 1950, Serial No. 10,346

Term of patent 14 years

(Cl. D48—4)

To all whom it may concern:

Be it known that I, Clyde D. McCann, a citizen of the United States, residing at Des Moines, in the county of Polk and State of Iowa, have invented a new, original, and ornamental Design for a Fluorescent Lighting Fixture, of which the following is a specification, reference being had to the accompanying drawing, forming a part thereof.

Fig. 1 is a left side elevational view of a fluorescent lighting fixture, showing my new design;

Fig. 2 is a front elevational view;

Fig. 3 is a right side elevational view; and

Fig. 4 is an end elevational view.

I claim:

The ornamental design for a fluorescent lighting fixture, substantially as shown.

CLYDE D. McCANN.
